United States Patent Office.

THOMAS W. MURRAY, OF NEW YORK, N. Y.

Letters Patent No. 75,696, dated March 17, 1868.

IMPROVEMENT IN RUDDERS.

The Schedule referred to in these Letters Patent and making part of the same.

TO ALL WHOM IT MAY CONCERN:

Be it known that I, THOMAS W. MURRAY, of the city, county, and State of New York, have invented a new and improved Device for Operating the Rudders of Vessels; and that the following description, taken in connection with the accompanying drawings, hereinafter referred to, forms a full and exact specification of the same, wherein I have set forth the nature and principles of my said improvement, by which my invention may be distinguished from all others of a similar class, together with such parts as I claim, and desire to have secured by Letters Patent.

This invention consists in constructing the rudder of two pieces, the lower part forming the blade, being somewhat similar to the lower part of the rudder now in use, but the upper portion or post is entirely dissimilar, being constructed independently of the blade, and is composed of a shaft of iron or other metal, bent in the form of a crank, and is connected with the blade at its outer edge instead of the inner.

The objects of the invention are to control the blade of the rudder at a point situated at its outer edge, or at the circumference of the circle, instead of at the centre; to prevent the bending and twisting off of the post, which is so frequent an occurrence with the ordinary rudders now in use; to keep the metal post free from immersion in water, by placing the same entirely above the water-line. In the accompanying sheet of drawings—

Figure 1 is a side view of my invention, applied to a vessel, partly in section.

Figure 2 is a plane view of the post or shaft, showing its connection with the blade and stern-post.

A represents the post or shaft, bent in the form of a crank, and is composed of iron or other metal. B is a metal band or strap, holding the post A in position. In the latter there is turned a recess or groove, into which the band fits, thereby preventing the post from rising or falling. C is the blade of the rudder, which is of wood or iron, as may be the case with the vessel. D is the stern-post, on which the band B is firmly bolted, and the blade C hung. E is a vertical pin, firmly secured to the outer edge of the blade C, and fitting into a corresponding hole made in the outer extremity of the post A. The pin E should be jacketed with rubber, to relieve in a measure the sudden strain on it and the post, caused by heavy seas striking the blade, as well as to prevent the constant rattle that would ensue, should the metal pin and post be directly in contact.

By the use of this device, it is believed that the frequent loss of and damage to vessels, occasioned by the twisting off of the rudder-posts now used, will be prevented.

Having thus described my invention, I claim as new, and desire to secure by Letters Patent—

The shaft A, formed with a crank upon its lower end, when used in combination with the rudder-blade C, to which it is connected at its outer edge by means of a pin or pivot, substantially as and for the purpose herein set forth.

THOMAS W. MURRAY.
